UNITED STATES PATENT OFFICE.

MAURICE GUSTAVE EUGÈNE ROCHAS, OF PARIS, FRANCE, ASSIGNOR TO FERNAND LOUIS BIELLE AND SOCIETE ROCHAS FILS & MILLET, BOTH OF PARIS, FRANCE.

SETTING PROVIDED WITH REMOVABLE STONES.

Application filed June 27, 1927, Serial No. 201,881, and in France July 8, 1926.

Jewels provided with removable stones, such as those which are changed every month generally present a mounting constituted by a frame arranged on the top of the bezel 5 of the ring.

Jewels thus made have the inconvenience of catching, of permitting the accidental opening of their frame and of letting their stones fall, so that the series of spare stones 10 becomes incomplete.

The present invention has for its object an improvement in jewels provided with removable stones for the purpose of remedying the above-mentioned inconveniences.

15 The improvement consists in making the bezel of the ring in such a manner that it can stop the stone placed in position after causing it to pass underneath, whilst a frame or bottom mounted under the bezel by 20 means of a hinge, prevents the stone from receding or from moving relatively to its normal position.

The stone is changed, after having taken the ring off the finger, or the bracelet from 25 the wrist, as the case may be, then, after having opened the frame or bottom, the latter is caused to rock on its hinge pin, so that this frame or bottom is not disengaged from the ring or bracelet during this opera- 30 tion.

This invention will be described herein- 35 after, by way of example only, with reference to the accompanying drawing in which:

Fig. 1 is a front elevation, partly in sec- 40 tion, of a ring embodying the said improve- 35 ment.

Fig. 2 is a cross vertical section of the 45 same ring made according to line A—A of Fig. 1.

Fig. 3 is a detail view showing the frame or bottom open, and without stone.

Fig. 4 shows another form of carrying out the invention, the ring being cut parallel to the finger, the bottom of the bezel being 45 open.

Fig. 5 is a view corresponding to Fig. 4, but the bottom of the bezel being closed.

Fig. 6 is a cross section of the ring made at right angles to the finger, the bottom of 50 the bezel being open.

Fig. 7 is a plan view of the movable bot- 55 tom of the bezel.

Fig. 8 is a fragmentary horizontal sec- 60 tional detail.

As illustrated in the drawing, Figs. 1 to 55 3, the bezel *a* of the ring, for instance, has on its outer edges any suitable stop member *a*¹ capable of preventing the stone from passing through when it is placed in position by causing it to pass underneath the bezel. This 60 stop member can be constituted by any small abutment, a bead, claws, etc.

This bezel *a* is perforated on the inner side for the passage of the stones and receives on the underside a frame or bottom 65 *b* mounted on a hinge *b*¹.

The stone *c* is inserted in the bezel *a* of the ring by causing it to pass underneath, after having opened the frame or bottom *b*.

This frame is then closed again, so that 70 it pushes the stone *c* in the bezel *a* until this stone presses by its front edge against the stop *a*¹ existing on the inner periphery of the said bezel. In this way, the stone *c* is held at the front by the stop *a*¹ and at the 75 rear by the frame or bottom *b* which prevents it from receding or from turning.

The frame or bottom *b* can be provided with any fastener, but the resiliency of the metal is usually sufficient for maintaining it 80 closed, so much the more as the contact of the finger naturally prevents it from opening.

In the form of construction illustrated in Figs. 4 to 7, the bezel *a* on the inner side of 85 the ring is provided with a frame or bottom *b* mounted on a hinge *b*¹ and capable of being closed by bringing it in a rabbet *b*² formed in the bezel.

A cam-piece *d* provided with a spring and 90 a push piece, arranged on the edge opposite to the hinge, holds the bottom *b* closed.

On the bottom *b*, on the inner side, is ar- 95 ranged a spring frame *e* adapted to resili- 100 ently press the stone against the shoulder *a*¹ of the bezel, provided on the side opposite to this bottom.

A resilient device causes the bottom *b* to automatically open when the cam-piece *d* is released. This device consists in a small re- 100 turning spring finger *f* pressing on the bot- 105 tom *b* near the hinge *b*¹ of the latter.

After having inserted a stone in the bezel through the interior of the ring, the bottom *b* is closed again and presses, through the 105 medium of its spring frame *e*, upon the back of the stone by pushing the latter against the shoulder *a*¹ of the bezel. During this

closing operation, the cam-piece *d* is compressed, then it retains the bottom *b* when the latter comes against the rabbet *b*².

By pressing upon the push piece *d*, after 5 having taken the ring off the finger, the bottom *b* automatically opens about its hinge *b*¹ under the action of the spring *f*, so that the stone can be released and replaced by another stone corresponding to the month of 10 the year.

It is to be understood that the application of the invention is not limited to a ring, as it might be applied quite as well to a bracelet, a necklace, a brooch, a pendant, etc.

15 The forms, details, accessories, materials and dimensions of the above device can of course be varied.

Claim:—

In an article of jewelry, a setting for re-

movably receiving stones of different colors 20 including in combination, a bezel having an open top and bottom, a shoulder at the top of the bezel, a bottom plate pivoted to the lower edge of the bezel, a spring member adapted to normally hold the bottom plate 25 extended, a spring pressed finger piece mounted for lateral movement in the bezel, co-operative catch means on the edge of the plate and finger piece, and a spring frame on the upper surface of the bottom plate 30 adapted to yieldingly press a stone against the shoulder on the bezel.

The foregoing specification of my "im- 35 provement in jewels provided with removable stones" signed by me this 17th day of June, 1927.

MAURICE GUSTAVE EUGÈNE ROCHAS.
